UNITED STATES PATENT OFFICE.

WILLIS A. GIBBONS, OF FLUSHING, NEW YORK, ASSIGNOR TO THE GOODYEAR'S INDIA RUBBER GLOVE MANUFACTURING COMPANY, A CORPORATION OF CONNECTICUT.

PROCESS OF FORMING AEROPLANE STRUCTURAL ELEMENTS.

1,269,420.

Specification of Letters Patent. Patented June 11, 1918.

No Drawing.

Application filed September 25, 1916. Serial No. 122,139.

To all whom it may concern:

Be it known that I, WILLIS A. GIBBONS, a citizen of the United States, residing at Flushing, L. I., county of Queens, and State 5 of New York, have invented certain new and useful Improvements in the Processes of Forming Aeroplane Structural Elements, of which the following is a full, clear, and exact description.

10 This invention relates to processes of manufacturing aeroplane structural elements embodying a hard rubber containing sheet, and has for an object to provide a process for more smoothly and more effectively 15 applying a sheet of this character to its supporting frame than has hitherto been possible.

Hard rubber treated fabric is particularly adapted for use in the manufacture of 20 aeroplane structural parts such as wings, pontoons, etc., on account of possessing very little stretch, considerable stiffness, and being unaffected by weather conditions. However difficulty has been experienced in 25 accurately shaping this material to the contour of a wing frame or other supporting frame, on account of the material having so little stretch at atmospheric temperature that it resists distortion and has a tendency 30 to maintain a flat or plane condition. Furthermore in the construction of wings particularly, it is desirable that the sheet exert a tension on the frame to enhance the rigidity of the unit, but hitherto the 35 hard rubber sheet has not accomplished this on account of its resistance to being tensioned.

The present invention obviates the above difficulties by heating the sheet to give the 40 hard rubber greater extensibility, and stretching taut and securing the heated sheet to the frame under tension. While cooling, the sheet shrinks and assumes perfectly the contour of its supporting frame, 45 and at the same time supplies the desirable tension to the frame.

In carrying out the invention, I have found it desirable to heat the sheet at localized portions after it has been fastened to 50 the supporting frame by some temporary means such as tacks. I have found it practical to carry out the heating step by first stretching the sheet as much as possible, lightly tacking it to the frame, and then warming with a flat iron. After each por-

tion is warmed, the tacks are removed, tension is applied to the warmed area from the edges of the sheet, and then while held taut under tension the heated portion is retacked to the frame. Then the next contiguous 60 portion is treated in like manner, and the operation is continued progressively until the tensioned sheet is completely fastened to the frame. Permanent fastenings, such as 65 lacings may be made later.

As above stated, hard rubber treated fabric when cold, or at atmospheric temperature, has very little stretch so that when fastened temporarily to the wing it retains its flat or plane condition. However, when 70 warmed, as for instance, by an electric flat iron, the rubber becomes flexible and elastic, the rubber treated sheet then having a degree of extensibility approximately equal to that of untreated fabric. In this condition the sheet can be drawn tightly to 75 conform perfectly to the contour of the supporting means, such as the ribs of a wing frame. When permanently fastened and allowed to cool the rubber regains its original stiffness and at the same time shrinks, 80 producing a still greater degree of tautness, thus supplying the desirable tension to the frame.

It is of course, not essential to fasten the 85 fabric before heating. The temporary fastening may be dispensed with. Likewise it is not essential to heat locally. The entire surface may be warmed simultaneously. Also the heat may be applied by any suitable method.

Having thus described my invention, what I claim as new and desire to protect by Letters Patent is:

1. The process of forming aeroplane 95 structural elements consisting of heating a hard rubber treated sheet to give it greater extensibility, while warm stretching the sheet taut, securing the taut sheet to a supporting frame, and permitting the sheet to 100 shrink.

2. The process of forming aeroplane structural elements consisting of temporarily applying to a frame a sheet of fabric treated with hard rubber, heating the sheet 105 to give the rubber greater extensibility, while warm stretching the sheet taut, securing the taut sheet to the frame, and permitting the sheet to shrink.

3. The process of forming aeroplane 110

2
wings, consisting of heating a hard rubber containing sheet to give it greater extensibility, stretching and securing the heated sheet to a wing frame, and permitting the sheet to shrink.

4. The process of forming aeroplane wings, consisting of temporarily applying to a wing frame a sheet of fabric treated with hard rubber, heating the sheet to give it greater extensibility, stretching the heated sheet, securing the sheet to the frame under tension, and permitting the sheet to shrink.

5. The process of forming aeroplane wings, consisting of temporarily fastening to the wing frame a sheet of fabric treated with hard rubber, progressively heating the sheet at localized portions, stretching the portions heated, securing said portions to

the frame under tension, and permitting the sheet to shrink.

6. An aeroplane structural element comprising a frame, and a hard rubber treated sheet shrunk on and supplying tension to the frame.

7. An aeroplane structural element comprising a frame, and a hard rubber treated sheet of fabric shrunk on and supplying tension to the frame.

8. An aeroplane wing or the like comprising a frame, and a hard rubber treated sheet of fabric shrunk on and supplying tension to the frame.

Signed at New York, county and State of New York, this 13th day of September 1916.

WILLIS A. GIBBONS.
